Att'y.

UNITED STATES PATENT OFFICE.

ELLIS H. MILLS, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTRICAL RELAY.

Application filed December 22, 1920. Serial No. 432,416.

To all whom it may concern:

Be it known that I, ELLIS H. MILLS, a citizen of United States, residing at East Orange, in the county of Essex, State of New Jersey, have invented certain new and useful Improvements in Electrical Relays, of which the following is a full, clear, concise, and exact description.

This invention relates in general to electrical relays and particularly to a structure for use on alternating current circuits in which means is provided for improving the contacts.

In telephone circuits it is necessary to employ relays which are operated by alternating currents of comparatively low frequency, such for example, as are employed in ringing circuits in which case the frequency employed is in most cases approximately $16\frac{2}{3}$ cycles per second. With such relays more or less trouble is experienced due to the fluttering of the relay armatures, resulting in low contact pressures and in extreme cases, intermittent contacts. In order to obtain satisfactory contact, it has, therefore, been the general practice to employ a much larger number of ampere turns on alternating current relays than it has been necessary to employ on similar relays operated in direct current circuits.

The object of the present invention is to provide a relay for use in alternating current circuits in which satisfactory contacts may be obtained without resorting to the use of an excessive number of ampere turns for the operation of the relay. To accomplish this object and in accordance with a feature of the invention, an inertia member is used in connection with the vibrating armature to prolong the time of contact for each pulsation of the alternating or fluctuating currents.

In accordance with another feature of this invention, the inertia member is so arranged as to be easily assembled upon relays of the standard type, and additional means are provided to insure that the relay operates most satisfactorily on currents of different frequencies.

These and other features of the invention may be more fully understood by reference to the accompanying drawing in which there is shown in perspective a structure embodying the features of the invention.

Referring more particularly to this draw-

ing, there is disclosed a relay of the standard flat type provided with an operating winding or coil 5 having a core extending therethrough provided with a pole piece 6 and a rearwardly extending clamping portion 7. A substantially U shaped armature 8 is secured to the clamping plate 7 by means of flexible hinge members 9, 9 which are riveted or otherwise securely attached to the lugs 10 and 11 of armature 8. A threaded pin 12 is securely fastened to the core 6 and extends as shown through an opening in the armature 8. Upon this pin is threaded an adjusting nut 13 which has a shoulder portion adapted to engage the armature 8 and serve as a backstop to limit its travel. The armature 8 is provided with a contact stud 14 which, in its movement, is adapted in the normal position of the armature to engage a contact spring 15, and in the operated position to engage contact spring 16. These contact springs are held in place by means of screws 17 and contact plates 18 and 19, and are insulated from each other and the clamping portion 7 by means of strips 20, 20 of hard rubber or similar insulating material. Adjusting screws 21 and 22 are arranged to bear against the bevelled portions of the contact springs 16 and 15 respectively, and are provided at their ends with insulating portions 23, 23. Upon the armature leg 11 there is riveted or otherwise securely fastened, a flexible spring member 24, upon which a weight member 25 is held by means of the screw 26. The weight 25 is so positioned upon the spring 24 that the natural period of the member is substantially that of the frequency of the pulsations of the alternating or fluctuating current upon which the device is to be operated.

Upon the flow of current in the operating coil 5 the armature 8 is attracted to pole piece 6, and contact 14 engages contact spring 16. As the wave form of the operating current approaches zero, there would naturally be a tendency for the armature 8 to be forced away from the pole piece 6 by means of the tension of contact spring 16 and the tension of the spring hinged members 9, 9. This tendency, however, is overcome in the present structure by means of the inertia of the weight 25 which is acting to maintain the contacts in a closed position until such time as the wave form again

reaches the necessary amplitude to provide an operating flux which will be great enough to overcome the spring pressure. In the structure as disclosed, there is a certain amount of flexibility in the hinged members 5 9, 9, so that when the armature is in its attracted position it pivots about the contact point 14, thus allowing the armature leg 11 to vibrate to a slight degree, which in 10 turn keeps the spring 24 in vibration and maintains the contacts closed. In other types of relays, the vibration of the spring 24 may be maintained by employing flexible contact springs having sufficient travel 15 to allow the armature to vibrate a slight amount without opening the contacts.

What is claimed is:

1. An electrical relay comprising an energizing winding having a core extending therethrough, an armature pivoted upon the core, a contact member adapted to be engaged by the movement of said armature, and an inertia member flexibly secured to said armature to prolong the time of contact closure when operating with fluctuating currents.
2. A relay comprising a winding having a core extending therethrough; a vibrating armature cooperating with said core; a pair 30 of contacts operated by the movement of said armature; a flexible reed secured to the armature and vibrating therewith, said

reed having movement relative to said armature; and a weight secured to said reed.

3. A relay comprising a winding having a core extending therethrough; a vibrating armature cooperating with said core; a pair of contacts operated by the movement of said armature; a flexible reed secured to the armature and vibrating therewith, said reed having movement relative to said armature; and a weight adjustably secured to said reed.

4. A relay comprising a winding having a core extending therethrough; a vibrating armature engaging the core, a pair of contacts operated by the movement of said armature, and a flexible weighted reed secured to the armature said reed having a natural period substantially equal to the fluctuations in the operating current.

5. A relay comprising a winding having a core extending therethrough, a vibrating armature engaging the core, a pair of contacts operated by the movement of said armature, and a flexible weighted reed secured to and substantially parallel to said armature, said reed having a natural period substantially equal to the fluctuations in the operating current.

In witness whereof, I hereunto subscribe my name this 17th day of December A. D., 1920.

ELLIS H. MILLS.
